CLAIM

The ornamental design for a latching bracket for the lower end of a support arm of a retractable awning, as shown.

DESCRIPTION

FIG. 1 is a perspective view of the latching bracket for the lower end of a support arm of a retractable awning embodying my new design;

FIG. 2 is a left side elevational view thereof;

FIG. 3 is a front elevational view thereof;

FIG. 4 is a top plan view thereof;

FIG. 5 is a rear elevational view thereof;

FIG. 6 is a bottom plan view thereof.
